D. R. SATTERLEE, OF NEW HAVEN, CONNECTICUT.

Letters Patent No. 77,105, dated April 21, 1868.

IMPROVED MACHINE FOR THE MANUFACTURE OF SLATE-PENCILS.

The Schedule referred to in these Letters Patent and making part of the same.

TO ALL WHOM IT MAY CONCERN:

Be it known that I, D. R. SATTERLEE, of New Haven, in the county of New Haven, and State of Connecticut, have invented a new Improvement in Machines for Making Slate-Pencils; and I do hereby declare the following, when taken in connection with the accompanying drawings, and the letters of reference marked thereon, to be a full, clear, and exact description of the same, and which said drawings constitute part of this specification, and represent, in—

Figure 1, a side view,

Figure 2, a top view,

Figure 3, a longitudinal section through the cutters, and in

Figure 4 a transverse section through the rear cutter.

Figures 5, 6, and 7, the construction of the cutters.

This invention relates to an improvement in the manufacture of pencils from slabs of slate or other material, the object being to construct a machine, which, receiving the slab at one point, automatically conducts the slab into the machine, and, passing through, the pencils are completely formed, and so discharged from the machine; and the invention consists in combining, with the proper feeding-rolls, two series of cutters, to operate upon opposite sides of the slab, and having arranged grooved beds or plates corresponding to the cutters, and in such relative position to the cutters that the said grooved plates or bed conduct and support the slab while being cut, and the pencils after they are cut.

To enable others to construct and use my improvement, I will proceed to describe the same as illustrated in the accompanying drawings.

A is the frame of the machine, of any convenient form and construction, upon which, in proper bearings, is arranged a cutter-shaft, B, provided with cutters, *a*, the said cutters constructed in the following manner, as seen in figs. 5, 6, and 7:

The two heads, L, are formed with a flange around their edge, as seen in fig. 4, and in each of the said heads are formed radial grooves, *f*, as seen in fig. 6, one edge of the said grooves being in a line radial to the centre of the said head, and the grooves corresponding in number to the number of cutters. The cutters shown in perspective, fig. 7, are formed of a solid piece of metal, provided at each end with a projecting lug, *h*, which sets into a groove in each of the heads, so that the upper edge of the cutter will bear against a flange around the inner edge of the head, and each of the said cutters grooved, as seen in fig. 7, each groove corresponding to one-half of the pencil to be cut, and the number of grooves to the number of pencils to be cut. The several cutters, arranged in their respective grooves around the head, present the cutting-points *i*, as seen in fig. 5.

The two heads, with the cutters inserted, are bolted together in any convenient manner, so as to hold the cutters firmly in their proper position; then when, from use, it shall be necessary to sharpen the cutters, remove them from the head and grind from the edge, that is, upon the surface, between one cutter and the next; then reinsert the cutters in their proper position. This grinding in nowise disturbs the grooves, but would shorten the point, so that it would not naturally bear against the flange around the head; therefore, to adjust the cutters, and always retain them in their proper position, that is, bearing against the flange of the head, I insert through the several cutters set-screws, as denoted at *n*, fig. 5, which pass through the cutters and bear upon the shaft, so that, by turning the screws into the cutters, the cutters will be forced out until they bear against the flange upon the edge of the head, and thus the said flange on the head acts as a guide for setting the cutters, and insures their being set always in the right position, and prevents any possible error in the setting.

Beneath the first cutters, *a*, is arranged a flat fixed bed, C, above which are arranged, in proper bearings, elastic feed-rolls, D. Forward of the cutters *a*, and below, are arranged other similar feed-rolls E, as seen in fig. 3, and above the said feed-rolls, a grooved plate, F, (see figs. 3 and 4,) grooved to correspond to the first cutters, *a*, and beneath the said plate F, and forward of the feed-rolls E, are arranged upon a shaft, H, cutters like or similar to the cutters *a*, and so that, with the grooves in the plate F, they form completely round spaces, as seen

in fig. 4. Forward of the last cutter is arranged a bed, I, grooved in like manner to the plate F, as seen in fig. 2, and so as to correspond to the last cutter, and above the bed I are arranged other elastic feed-rolls, k.

The feed-rolls and cutters are caused to revolve by belts applied thereto, as seen in fig. 1, or in other convenient manner. The cutters should revolve so as to cut back toward the feed-rolls, that is to say, should revolve in an opposite direction to the feed-rolls. The feed-rolls are provided with springs, d, to allow them to yield to different thicknesses of the material to be cut. The slab is entered upon the bed C, and passed in to the rolls D, and by the said rolls D is presented to the first cutters, a, which cut into the slab, and form one-half of the pencils. The cut or grooved slab advancing, passes into the grooves in the plate F, and supported by the rolls E, is advanced to the under cutters, which cut the under surface of the slab in like manner as the first cutters cut the upper side, and separate the pencils, and form them completely round. The slab still advancing, the cut pencils enter the grooves in the bed I, and beneath the rolls k, and are thus conducted from the machine to be cut to their proper lengths. Thus the machine, receiving the slab at the rear end, conducts it through, forming the pencils completely round, and in the most perfect manner, and discharging them finished at the formed end, and this without the intervention of manual labor, from the entrance of the material to the exit of the pencils.

Having thus fully described my invention, what I claim as new and useful, and desire to secure by Letters Patent, is—

1. The combination of the two series of cutters, each series formed so that the first half forms the pencil, and while the second completes the pencil, and combined with the grooved plate F and correspondingly grooved bed I, in relative position to each other, and to the two series of cutters described, so as to form guides from the first series of cutters to the second, and from the second to the discharge, substantially in the manner herein set forth.
2. In combination with the above, I claim the feed-rolls D and k, arranged and operating in the manner substantially as described.
3. The arrangement of the cutters between the heads L, so as to be set and adjusted, substantially in the manner described.

D. R. SATTERLEE.
